REMOVAL OF LIQUID REFRIGERANT FROM
THE SUPPLY LINE TO A COMPRESSOR

Joseph W. Obreiter, Jr., Glen Ridge, N. J.

Application September 17, 1947, Serial No. 774,643

10 Claims. (Cl. 62—115)

1
This invention relates to refrigeration and more especially to the removal of liquid refrigerant from the supply line of a compressor. The invention is concerned with refrigeration systems that have a closed circuit in which the refrigerant passes successively through a compressor, condenser, and evaporator; and then back to the intake side of the compressor.

Any liquid refrigerant that is not vaporized in the evaporator, and that travels back to the compressor, endangers the compressor lubrication by mixing with the compressor crankcase oil, or even washing out compressor crankcase oil via the compressor discharge. Liquid refrigerant reaching the compressor inlet is also dangerous because of the possibility of damage to the compressor from slugs of the liquid refrigerant and oil.

It is an object of this invention to provide an improved method and apparatus for removing liquid refrigerant from the conduit between an evaporator and the intake side of a compressor.

One feature of the invention relates to apparatus in which liquid refrigerant is removed from a compressor supply line, in which there is entrained oil, without having the separation apparatus become oil logged. Another feature relates to the vaporizing of any liquid refrigerant that passes beyond the evaporator, and to simple apparatus in which the liquid refrigerant is vaporized and the vapor returned to the system without interfering in any way with the efficient operation of the refrigeration cycle. The preferred form of the invention may increase the efficiency of the refrigeration system with which it is used.

Other objects, features and advantages of the invention will appear or be pointed out as the description proceeds.

The drawing is a diagrammatic illustration of the preferred form of the invention.

The refrigeration system shown in the drawing includes a compressor 10 that delivers compressed refrigerant, in vapor phase, through an outlet pipe 11 to a heat exchanger 12. The refrigerant vapor passes through the heat exchanger 12, and piping 13, to a condenser 14.

In the condenser 14 the refrigerant is condensed to a liquid and discharged through condenser outlet piping 17 to an expansion valve 18. The condenser 14 is shown with connections 20 and 21 for the supply and discharge of cooling liquid, such as water, that is used to extract heat from the condenser.

Beyond the expansion valve 18, the refrigerant

2
passes into an evaporator 24; and the outlet of the evaporator is connected by piping 25, with a separator 26. The outlet of the separator is connected with the intake of the compressor 10 by a conduit 28.

A thermostatic controlling mechanism is connected with the expansion valve 18, and this mechanism consists of a bulb 30 located adjacent the low pressure or hot side of the evaporator 24, and a capillary tube 31 through which the valve 18 is actuated with the development of a temperature in excess of that required in the operation of the apparatus when the load upon the evaporator is well below its peak. The bulb 30 is preferably strapped to the piping 25. This control feature is old and well known in the refrigerating art.

The separator 25 is a gravity separator and the piping 25 opens into the separator 26 at a region 20 somewhat below the top of the separator. A tapering outlet 34, at the top of the separator 26, is connected with the conduit 28 by a fitting 35. When the refrigeration system is in operation, vaporized refrigerant from the piping 25 follows 25 the course indicated by the dotted arrow 37 and passes directly to the outlet 34, and through the conduit 28 to the intake side of the compressor 10.

Liquid refrigerant and oil flow by gravity, as 30 indicated by the dotted arrow 40, toward a bottom wall 41 at the lower end of the separator 26. In the construction illustrated, the bottom wall 41 of the separator 26 comprises the top of the heat exchanger 12, but it will be understood 35 that the separator 26 and heat exchanger 12 can be separate units connected by the necessary conduits.

Liquid that gathers in the bottom of the separator 26 drains downward through a tubing 43 and through a check valve 44 near the upper end of the tubing. The liquid refrigerant from the tubing 43 enters a coil 46, and while the refrigerant is in the tubing 43 and coil 46, it is in heat-exchanging relation with the hot compressed gases that flow through the heat exchanger 12 and into contact with the outside surfaces of the tubing 43 and coil 46.

The liquid refrigerant that is vaporized in the coil 46, and in the tubing 43 below the check valve 44, cannot flow back through the tubing 43 because of the check valve. The vaporized refrigerant escapes from heat exchanger through an outlet pipe 48 that discharges into the outlet 50 34 of the separator 26. As soon as the liquid in the coil 46 has been vaporized, back pressure

against the check valve 44 is relieved, and more liquid from the separator 26 can flow downward through the tubing 43 and check valve 44.

The refrigeration system includes a closed circuit, and the liquid that is separated from the gas stream in the separator 26 can be considered as withdrawn from the circuit and later returned to the circuit when it is vaporized and again enters the stream of evaporated refrigerant flowing from the evaporator 24. By thus withdrawing the liquid, heat can be applied to it without increasing the temperature of the evaporated refrigerant passing from the evaporator to the compressor. Another advantage is that the pressure in the heat exchanger in which the separated liquid refrigerant is vaporized need not be the same as in the low pressure side of the refrigerant circuit. For example, when the liquid in the coil 46 is being vaporized, the pressure in the coil will at times be higher than the pressure in the piping 25, and must be higher in order to hold the check valve 44 closed. This higher pressure causes increased velocity at the discharge end of the pipe 48 and the flow of vapor from the end of the pipe 48 into the tapered outlet 34 gives an aspirator action that aids the flow of evaporated refrigerant from the pipe 25 into the separator outlet 34.

It is a feature of the invention that the liquid evaporated in the coil 44 discharges into the separator 26 above the level of the liquid in the separator. This permits the vaporized refrigerant to be discharged from the coil 46 at a sufficiently high velocity to entrain oil and carry it, entrained in the vapor, back through the conduit 28 to the compressor. If there were no check valve 44 and the vaporized refrigerant from the coil 46 escaped upward through the tubing 43, and through the accumulated liquid in the bottom of the separator 26, the velocity of the vaporized refrigerant would be considerably lower and the sump of the separator might become oil logged.

It is also a feature of the invention that the discharge end of the pipe 48 is not only located above the liquid level in the separator but is also located above the level at which the piping 25 opens into the separator 26. This means that the vaporized refrigerant from the pipe 48 enters into the stream of vapor passing to or through the outlet 34 and does not encounter the downwardly moving particles of liquid refrigerant and oil from the piping 25.

It will be understood that the piping 48 can communicate with the conduit 28 beyond the separator 26 and still embody this feature of having the vaporized refrigerant from the heat exchanger 12 join the vaporized refrigerant from evaporator 24 at a region beyond that at which liquid and vapor from the evaporator were separated.

The heat exchanger 12 is merely representative of apparatus for heating the liquid refrigerant from the separator 26. By making use of the refrigerant, on the high pressure side of the evaporator, as the source of heat for the heat exchanger 12, the refrigerant reaches the evaporator 24 at a lower temperature and produces more cooling in the evaporator. The efficiency of the system is thus increased.

It is not necessary, however, to use the refrigerant on the high pressure side of the compressor as the source of heat for evaporating the liquid from the separator 26, and in cases where the separator is not located close to the compressor or condenser, it may be advantageous to use other

sources of heat to evaporate the liquid refrigerant that is collected by the separator 26.

Various changes and modifications can be made in the form of the invention described, and some features of the invention can be used alone or in different combinations without departing from the invention as defined in the claims.

I claim as my invention:

1. In the operation of a refrigeration system in which compressed refrigerant is condensed, evaporated to produce refrigeration, and returned to a compressor, the improvement that comprises withdrawing any remaining liquid refrigerant from the evaporator refrigerant at a region along the course of circulation of the evaporated refrigerant through the system, transferring the liquid to another region of higher temperature, vaporizing said withdrawn liquid by the application of heat at the region of higher temperature, and returning the resulting vaporized refrigerant to the course of circulation of the evaporated refrigerant along a course that by-passes the region at which the liquid was withdrawn and at a region downstream from that at which said liquid was withdrawn at a region beyond that at which the liquid was withdrawn from the evaporated refrigerant and ahead of the intake of the compressor.

2. In the operation of a closed-circuit refrigeration system in which compressed refrigerant is condensed, evaporated, recompressed and repeatedly circulated through the system, the improvement that comprises withdrawing from the evaporated refrigerant any oil and other entrained liquid, draining such liquid from the refrigeration circuit, returning the oil to the refrigeration circuit by entraining the oil in refrigerant that is evaporated from the liquid state at the region to which the oil is drained, the entrained oil being returned to the circuit by a course different from the course through which the oil was drained, and returning the entrained oil to the circuit at a region down stream from that at which liquid was withdrawn from the evaporated refrigerant.

3. In the operation of a closed-circuit refrigeration system in which compressed refrigerant is condensed, evaporated and recompressed in repeated cycles, the improvement that comprises withdrawing oil and liquid refrigerant from the circuit at a region between the evaporator and the inlet of the compressor, heating said oil and liquid refrigerant until the liquid refrigerant is vaporized, and returning the vaporized refrigerant into the stream of evaporated refrigerant in the circuit, down stream from the region at which the oil and liquid were withdrawn, and with the oil entrained in and carried by the vaporized refrigerant.

4. In a refrigerating apparatus having a compressor, condenser, an evaporator and connections therebetween, means for preventing liquid refrigerant from reaching the compressor comprising a gravity separator in the connection between the evaporator and the compressor, a heat exchanger arranged to receive liquid refrigerant from the separator and hot gases from the compressor, and a connection for vaporized refrigerant from the heat exchanger to the intake side of the compressor.

5. In a refrigerating apparatus having a compressor, condenser, an evaporator and connections therebetween, means for preventing liquid refrigerant from reaching the compressor comprising a gravity separator in the connection between

the evaporator and the compressor, a heat exchanger, a connection between the bottom of the separator and one side of the heat exchanger, a source of heat at the other side of the heat exchanger, and a connection from the first mentioned side of the heat exchanger to the intake side of the compressor.

6. In a refrigerating apparatus having a compressor, condenser, an evaporator and connections therebetween, means for preventing liquid refrigerant from reaching the compressor comprising a gravity separator in the connection between the evaporator and the compressor, a heat exchanger, a connection between the bottom of the separator and one side of the heat exchanger, a check valve in said connection, a source of heat at the other side of the heat exchanger, and a connection from the first mentioned side of the heat exchanger to the intake side of the compressor.

7. In a refrigerating apparatus having a compressor, condenser, an evaporator and connections therebetween, means for preventing liquid refrigerant from reaching the compressor comprising a closed gravity separator in the connection between the evaporator and compressor, an inlet from the low pressure side of the evaporator entering the separator near its top, an outlet from the separator at the bottom for liquid refrigerant, an outlet from the separator near its top for gaseous refrigerant, a heat exchanger arranged to receive liquid refrigerant from the bottom outlet of the separator and to return gaseous refrigerant to the separator adjacent its top outlet.

8. In a refrigerating apparatus having a compressor, condenser, an evaporator and connections therebetween, means for preventing liquid refrigerant from reaching the compressor comprising a closed gravity separator in the connection between the evaporator and compressor, an inlet from the low pressure side of the evaporator entering the separator near its top, an outlet from the separator at the bottom for liquid refrigerant, an outlet from the separator near its top for gaseous refrigerant, a coil located externally

of the separator having one end connected with the bottom outlet of the separator and the other opening into the separator adjacent its upper outlet, a casing surrounding the coil and means to supply a heating fluid to said casing.

9. In a refrigerating apparatus having a compressor, condenser, an evaporator and connections therebetween, means for preventing liquid refrigerant from reaching the compressor comprising a closed gravity separator in the connection between the evaporator and compressor, an inlet from the low pressure side of the evaporator entering the separator near its top, an outlet from the separator at the bottom for liquid refrigerant, an outlet from the separator near its top for gaseous refrigerant, a coil located externally of the separator having one end connected with the bottom outlet of the separator and the other opening into the separator adjacent its upper outlet, a casing surrounding the coil, and connections from the compressor to the casing and from the casing to the condenser.

10. In a refrigerating apparatus including a compressor, a condenser, an evaporator, and connections joining the different elements of the apparatus in a closed system for circulation of refrigerant, a separator in the connection between the evaporator and the low pressure side of the compressor for preventing liquid refrigerant from passing to the compressor, a heat exchanger in position to receive liquid refrigerant from the separator, and connections for circulating refrigerant on the high pressure side of the evaporator through the heat exchanger to supply heat for evaporating the refrigerant from the separator.
